UNITED STATES PATENT OFFICE.

WILLIAM C. KING, OF UNION TOWNSHIP, ALLEGHENY COUNTY, PENNSYLVANIA, AND GEORGE B. SWIFT, OF WHEELING, WEST VIRGINIA, ASSIGNS TO KING, SON & CO., OF PITTSBURG, PENNSYLVANIA.

DESIGN FOR GLASSWARE.

SPECIFICATION forming part of Design No. 12,080, dated December 28, 1880.

Application filed October 25, 1880. Term of patent 3½ years.

To all whom it may concern:

Be it known that we, WILLIAM C. KING, of Union township, county of Allegheny, State of Pennsylvania, and GEORGE B. SWIFT, of 5 Wheeling, county of Ohio, State of West Virginia, have invented and produced a new and original Design for Glassware; and we do hereby declare the following to be a full, clear, concise, and exact description thereof, reference being had to the accompanying drawings, making a part of this specification, in which— like letters indicating like parts—

Figure 1 is a perspective view of a glass cream-pitcher, and Fig. 2 is a similar view of 15 a glass butter-dish, both being illustrative of our new design for glassware.

Our invention relates to a new design for glass table-ware, the distinctive features of which are shaping the sides or body of the article, both inside and outside, in a series or 20 number of curved segments or lobes, each such segment or lobe having a radius of curvature less than that of the general outline of the article as a whole; also, extending feet from 25 the lower extremities of such segments or lobes for supporting the article.

In the drawings we have illustrated our new design as applied to two different articles of glass table-ware, Fig. 1 showing a pitcher 30 with handle and spout, but without cover, while Fig. 2 shows our design in a covered dish.

The features which make up our new design in these articles are as follows:

35 The form of the body of the article, both the interior and exterior, is that of a series or number of curved segments or lobes, *aa*, arranged vertically and extending in succession around the body, each lobe or segment extending from 40 top to bottom of the body. The curvature of these lobes or segments is of less radius than that of the general outline of the body, as a whole, in any common horizontal section, thus giving the outline of both interior and exterior surfaces a waving appearance, as illus-

trated in the drawings. We prefer to make four of these lobes or segments *a*, one on each side of the article, giving it a quadrangular form, and from the lower extremity of each lobe feet *b* are extended below the bottom 50 for supporting the article. These feet may be fluted or reeded and curved, as shown, or other form be given them, as good taste may suggest, in adapting them to the general form and ornamentation of the article.

In covered dishes, Fig. 2, we employ the same lobed feature in the form of the cover, as above described in the body, as we consider the cover as belonging to and really forming a part of the body of the article.

55 Bands *c* or other ornamentation may be added to the article, as desired.

In handled ware the handle *e*, Fig. 1, is placed on one of the lobes, and in pitchers the pouring-spout is made in the opposite lobe.

60 This same design may be carried out or be embodied in a whole set of glass table-ware, and whether in sets or single articles the design is a pleasing and attractive one, readily distinguishable on account of its prominent characteristics, hereinbefore described, and for such 65 reasons articles embodying it meet with ready and profitable sale.

70 We claim as our invention—

The design for glassware shown and 75 described, consisting in shaping the body of the article, both inside and outside, in four segments or lobes arranged vertically, each segment or lobe having a curved outline of less radius than that of the general outline 80 of the body as a whole, and each segment or lobe having a foot extending from its lower extremity below the bottom of the article.

70 In testimony whereof we have hereunto set our hands.

WM. C. KING.
GEORGE B. SWIFT.
